UNITED STATES PATENT OFFICE

WILLARD F. CLARK, OF CHICAGO, ILLINOIS

DESIGN FOR A RADIATOR CAP ORNAMENT

Application filed December 30, 1932. Serial No. 46,666. Term of patent 3½ years.

To all whom it may concern:

Be it known that I, WILLARD F. CLARK, a citizen of the United States, residing at Chicago, in the county of Cook and State of Illinois, have invented a new, original, and ornamental Design for a Radiator Cap Ornament, of which the following is a specification, reference being had to the accompanying drawing, forming a part thereof.

Figure 1 of the drawing is a perspective of a radiator cap ornament embodying the new design;

Figure 2 is a plan view.

I claim:

The ornamental design for a radiator cap ornament substantially as shown.

Chicago, Illinois, November 19, 1932.

WILLARD F. CLARK.
